BOX

Walter A. Becker, Chattanooga, Tenn., assignor
to Old Dominion Box Company, Lynchburg,
Va., a corporation of Virginia.

Application December 16, 1940, Serial No. 370,370

3 Claims. (Cl. 229—23)

This invention relates to folding or knock-down boxes and more especially to boxes of this nature constructed for holding and displaying goods and such as cigars, candies, confections and the like. It is common practice to pack the above-named goods, especially cigars, in what is known as set-up wooden boxes. There are many disadvantages in using boxes of this type, all of which add considerably to the final cost of the marketed product. For example, set-up boxes occupy the same amount of space when they are empty as they do when filled; they are more expensive to manufacture; they are subject to a higher shipping rate; and finally, they occupy a greater amount of room on the packer's table when being filled, thus making it necessary to employ additional help to keep the packers supplied with empty boxes. Many elements enter to make the cost of the collapsible cardboard box more economical such as the adaptability of the collapsible box to machine manufacture and also to printing operations.

It is an object of this invention to provide a collapsible cardboard box for holding and displaying cigars and the like, which has substantially the same appearance and strength when erected as the conventional set-up wooden box heretofore used.

It is another object of this invention to provide a collapsible merchandise box of the class described in which means are provided for elevating the merchandise as it is sold, toward the top of the box. This feature is particularly important in the sale of cigars. When two or more layers of cigars are sold from a box, it is often required by cigar smokers that a new box be opened, because they feel that the remaining cigars are not fresh. This feeling is unfounded because cigars are usually wrapped in Cellophane which keeps them fresh for a long period, even though they are in an opened box. Notwithstanding this fact, however, it has been found to contribute to the salability of the goods to have means for elevating the goods as sold, so that the package will have a neater and fresher appearance.

It is another object of this invention to provide a collapsible box in which a removable liner is employed, for locking the same in erected position. This liner also serves to receive the merchandise and act as a support for the box lid when closed.

Some of the objects of the invention having been stated, other objects will appear as the description proceeds when taken in connection with the accompanying drawings, in which—

Figure 1 is a plan view of a blank from which my improved merchandise box is adapted to be formed;

Figure 2 is an isometric view showing the blank 60 The purpose of this flap is chiefly to provide re-

after the front sidewall flap has been folded upon itself and the corner sections secured to the end walls, and also after the lid portion has been folded and reinforced with an additional thickness:

Figure 3 is an isometric view of the erected box after the locking flaps have been placed in position within the box;

Figure 4 is a plan view of a liner blank for the box;

Figure 5 is an isometric view of the blank shown in Figure 4 after it has been assembled, erected and ready for insertion within the box shown in Figure 3;

Figure 6 is a plan view of a blank which is used as an elevating bottom to be supported by the liner when the liner is disposed within the box;

Figure 7 is an isometric view of the liner, shown with the collapsed elevating bottom disposed therein;

Figure 8 is a view similar to Figure 7 but showing the elevating bottom in an erected position;

Figure 9 is an isometric view of the box in combination with the liner and the elevating bottom;

Figure 10 is a transverse sectional view taken along the line 10—10 in Figure 9;

Figure 11 is a transverse sectional view at the end of the box and taken along the line 11—11 in Figure 9;

Figure 12 is a detail sectional plan view taken along the lines 12—12 in Figures 10 and 11;

Figure 13 is an isometric view of the completed box showing the lid secured in closed position by a suitable tack or nail;

Figure 14 is a transverse sectional view taken along the line 14—14 in Figure 13;

Figure 15 is a plan view of a liner blank similar to Figure 4 but showing the endwall extensions;

Figure 16 is an isometric view of the liner shown in Figure 15 after it has been erected;

Figure 17 is an isometric view of a box such as shown in Figure 3 in combination with the liner shown in Figure 16 and the elevating bottom such as shown in Figure 6.

In practicing the invention, a suitable blank made from flexible cardboard or the like is cut to the shape as shown in Figure 1. The present embodiment comprises a blank having a bottom portion 10, said portion having integral therewith, sidewall 11 joined thereto along bend line 12. Another bend line 14 is disposed along the outer edge of front wall 11, which serves as a line of demarcation between the front wall and a reinforcing flap 15. The flap 15 has one face thereof rendered adhesive as at 16, so that the flap can be bent inwardly along line 14 and secured to the inner face of the front sidewall 11. The purpose of this flap is chiefly to provide re-

inforcement to the front sidewall of the container.

Another bend line 17 is disposed on the opposite side of the bottom 10 and at the base of the rear wall. This rear wall is designated by reference character 18 and is substantially the same as the front wall 11 previously described except the reinforcing flap 15 is not provided. Integral with the upper portion of back wall 18 is a top flap 19, said top flap being joined to the upper edge of wall 18 along bend or crease line 20. This flap has bend lines 21, 22, 23 and 24 therein, thus providing five rectangular sections, namely, 26, 27, 28, 29 and 30. The sections 26, 27, and 28 have one face thereof rendered adhesive by the application of glue or other material which is designated by the reference character 32. During the formation of the box a suitable cardboard filler 34 is placed upon the section 26 and one face thereof is secured thereto by the adhesive. The section 27 is folded over one edge of the filler 34, and then the section 28 is folded over the other face of the filler. Both of the sections 27 and 28 are also secured to the cardboard material by the adhesive 32 previously described. When the lid portion has been completed, the members 26, 27, 28 and 34 will appear as one unit such as shown in Figure 2. The sections 29 and 30 are not attached to the cardboard 34 but merely extend downwardly into the box in the manner shown in Figure 3 adjacent the back sidewall 18.

The bottom portion 10 also has end walls 37 joined thereto along bend lines 38 and the free ends of each end wall has, in turn, joined thereto along bend line 39 suitable locking flaps 40. The sidewalls and endwalls are joined together at their corners by suitable triangular areas 45 and 46. These triangular sections are separated by diagonal crease lines 47 which crease lines substantially bisect the 90 degree angles at the corners between bend lines 12 and 38 as well as between bend lines 38 and 17. The triangular areas 46 preferably have suitable coatings of adhesive 49 applied thereto which is employed for attaching the same to the inner face of the end walls 37 in the manner shown in Figure 2.

In order to erect the collapsible box, the sidewalls 11 and 18 are pulled to a substantially vertical position and this action will, in turn, force the end walls 37 to a substantially vertical position. Then the end sections 45 and 46 will be doubled upon themselves so that their layers will occupy a position parallel to the end walls, and thus provide a suitable reinforcing truss member which will prevent the sidewall from spreading at the corners of the box. Locking flaps 40 will then be folded inwardly along lines 39, so that the free end of locking tab will be disposed in close proximity to the bottom 10 of the box in the manner shown in Figure 3.

These locking flaps 40 serve to hold the corner sections 45 and 46 in folded position; however, it must be borne in mind that it is necessary to have some additional means for preventing these flaps 40 from again moving upwardly and releasing these folded corner sections to permit the collapse of the box. Therefore, it has been found necessary to provide a suitable liner filler for the interior of the box which will hold the locking flaps 40 in erected position.

The liner which is used to hold the locking flaps 40 in position against the folded corner sections, is formed from a blank 55 (Figure 4). This blank is creased along lines 56, 57, 58 and

59 thereby forming areas or sections 60, 61, 62, 63 and 64. The areas 60 and 64 are covered with an adhesive 65 which is used for uniting these sections to the sections 61 and 63, respectively, to form sidewalls for the liner. In order to erect the liner, areas 60 and 64 are bent along lines 56 and 59 respectively toward the observer in Figure 4, and then folded downwardly against areas 61 and 63, thereby forming doubled sidewalls for the liner. Then the doubled sidewalls are bent away from the observer in Figure 4 along lines 57 and 58 to shape the liner in the position shown in Figure 5. Integral with each end of each of the areas 60 and 64 are suitable projections 68, these projections are adapted to fit in suitable notches 69 in the locking flaps 40, when the box is in an erected position. The notches 69 are clearly visible in Figures 1, 2 and 3, the position of the notch 69 in Figure 3 being such as to receive a projection 68 when the liner is inserted. Also Figures 11 and 12 show how the projections 68 fit into the notches 69 so that the liner will be held in position within the box to cause the locking flaps 40 to be held against the collapsed corner sections, which in turn are folded against the end walls 37 of the box.

Figure 10 also shows how the sidewalls of the liner cooperate with the sidewalls of the box. In the right-hand portion of Figure 10, the flap or section 30 which extends from the lid of the box, slidably fits into a suitable groove 72 which is disposed between the area 64 of the liner sidewall and the area 18 of the box. It is here seen that this flap covers the raw lower edge of the filler member 34 and conceals it from view when the lid is opened. Due to the fact that bend lines 23 and 24 are provided, the flap 30 will readily bend at the lower edge of the filler member 34 when the cover is opened and closed. Especial attention is called to the fact that the filler member 34 as well as the areas 27 and 28 are supported by area 26, which is united to the upper edge of the back sidewalls 18 along crease or bend line 20. Such a construction permits the entire lid to move downwardly within the confines of the box sidewalls and to rest upon the top edges of the liner sidewalls. This additional thickness of the lid has certain reinforcing advantages and also provides sufficient thickness for receiving a suitable nail 75 for holding the lid in closed position as shown in Figure 14. When the lid is lowered within the confines of the side and end walls the box is thereby made much stronger, and more capable for holding fragile goods such as cigars and the like. With the lid 26 in closed position, its edges fit against the end walls and sidewalls of the box as it rests on the top edges of the liner. This prevents the box from being bent out of rectangular position.

As heretofore stated, it is very essential to have means for elevating the goods in the box as the same are being used, so that the upper surface of the goods will occupy a position near the top edge of the box and give the appearance of a filled box. Also by raising the goods the inside of the end and sidewalls will be concealed from view. In order that a simple and convenient means may be employed for elevating the goods, an additional bottom is provided which is formed from a blank 76 (see Figure 6). This blank comprises a main bottom section 77 and adjacent flaps or legs 78, which legs are joined to the bottom section 77 along bend lines 79. Each of the extensions 78 has integral therewith a short projection 80 which is slightly narrower than notches

81 in the section 62 of the liner 55. The notches 81 have adjacent notches 82 which are narrower than the notches 81 or the projections 80. Therefore, the projections 80 can only fall in notches 81. It will be seen by observing Figure 6 that when the blank 77 is folded along scored lines 79 and inserted in the liner 55 that the projections 80 will fit in their respective notches 81 and be held in position so that the bottom portion 77 will be held in spaced relation to the bottom section 62 of the liner, and therefore the goods which rest upon the portion 77 will be raised nearer the top of the box.

When the box is filled with merchandise such as cigars 85 as shown in Figure 14, the leg projections 78 are adapted to be folded inwardly parallel to portion 77 and on top of section 62 (Figure 7).

In order to raise bottom portion 77, it is necessary to gain access to the collapsed legs or extensions 78 and rotate them about their crease lines until they assume a position substantially at right angles to the bottom of the box such as shown in Figures 8, 9 and 10. Suitable slots 86 are provided in the bottom area 10 of the box (Figures 1, 2 and 3). These notches substantially coincide with slots 82 in the liner bottom 62, said slots 82 and 86 being provided so that one's fingers may be inserted therethrough to contact the collapsed legs 78 and move them to erected position.

Projections 80 extend beyond the edge of legs 78 a distance substantially equal to the thickness of the section 62 of liner 55. It is seen by referring to Figure 10 that the bottom edges of the projections 80 are disposed in the notch 81 and rest upon the bottom 10 of the box. There is no particular objection to the slots 82 and 86 because the bottom area 77 serves to close these holes when the box is filled, and at all times this area shields the bottom portion of the material or merchandise within the box from view when looking through these slots, even though the bottom may be erected to elevated position as shown in Figure 9. The bottom 77 has suitable notches 87 cut in opposed ends thereof which are employed for inserting or removing this member from the box.

Figures 15, 16 and 17 show a slightly modified form of the invention which differs from the preceding form only in the construction of the liner. The improved liner is designated by the reference character 88 and the parts which are similar to the liner 55 previously described will be given like reference characters and the additions to the liner will be given new reference characters. The chief difference in this liner and the liner shown in Figures 4 and 5 is the fact that the ends of portion 62 have suitable end wall extensions 89 showing two portions 88 along crease or bend lines 90. Joined to the extensions 89 are suitable flaps 90 along bend or crease lines 92. Disposed upon one face of each of the slots 91 is a suitable adhesive 93 and this adhesive is used to unite the areas 91, 89 to form a solid end wall at each end of the bottom portion 62. Figure 16 shows the liner 88 when it has been erected and it is here seen that both the sidewalls and the end walls are substantially flush top so that when the same is placed inside of the box in the manner shown in Figure 17 that the four edges of the cover will be properly supported. Of course the elevating bottom 76 is adapted to be inserted within the liner 88 after the same has been placed within the box. The end walls of the liner 88 which are formed from areas of sections 89 and

91 are adapted to contact the locking flaps 48 of the box and hold the same in position. In turn, the end walls of liner 88 are held in erected position either by the goods within the box or by the elevating bottom such as shown in Figure 6.

In the drawings and specification, there has been set forth a preferred embodiment of the invention, and although specific terms are employed, they are used in a generic and descriptive sense only, and not for purposes of limitation, the scope of the invention being set forth in the appended claims.

I claim:

1. A paper box having a bottom, sidewalls, and end walls, one of said sidewalls extending beyond the top of the box and being folded inwardly upon itself to form a lid, a rigid cardboard filler secured between said folds, a flap integral with the free end of the inwardly folded portion slidably extending downwardly into the box adjacent the sidewalls, a liner in said box comprising a substantially rigid rectangular paper box of shallower depth than the first box and adapted to fit snugly in the first box, one wall of the liner partially covering said free end whereby the upper thickness only will be hinged to said sidewall and the hinge line will be concealed from an observer standing in front of the open box.

2. A paper box having a bottom, sidewalls, and end walls, one of said sidewalls extending beyond the top of the box and being folded inwardly upon itself to form a lid, a rigid cardboard filler secured between said folds, a flap integral with the free end of the inwardly folded portion slidably extending downwardly into the box adjacent the sidewall, a liner in said box comprising a rectangular paper box adapted to fit snugly in the first box and to press against the walls thereof and whose upper edges stop short of the upper edges of the walls of the box a distance approximately equal to the thickness of the lid, whereby the unattached edges of the lid will fit within the confines of the sidewalls of the box and rest upon the top edges of the liner so that when the lid is moved to closed position and attached to the front wall of the box, the side and end walls of the box are restricted from moving out of rectangular position, one wall of the liner partially covering said free end of the inwardly folded portion whereby the upper thickness only of the lid will be hinged to one of said sidewalls and the hinge line will be invisible to a person standing in front of the open box.

3. A rectangular paper box having sidewalls and end walls and having a rigid lid hinged to one of the sidewalls, a liner comprising a rectangular paper box adapted to fit snugly within the box, the upper edges of the liner being disposed below the top edges of the box a distance substantially equal to the thickness of the lid portion, the lid portion being adapted when in closed position to fit within the side and end walls, whereby when the free end of the hinged lid is secured to the box the lid will prevent movement of the sidewalls out of a rectangular position, the lid portion adjacent to the point where it is hinged to one of the sidewalls of the box having a flap extending downwardly into the box to cover the fold line between the lid and the box, said sidewalls having cavities therein and the liner having projections to fit into said cavities.

WALTER A. BECKER.
